JUG

John Brady Campbell, Paramus, N.J., assignor to The Clorox Company, Cincinnati, Ohio, a corporation of Ohio

Filed Sept. 28, 1966, Ser. No. 4,069

Term of patent 14 years

(Cl. D58—5)

FIG. 1 is a side elevational view of a jug showing my new design.

FIG. 2 is a top plan view of the same.

FIG. 3 is a rear elevational view of the same.

FIG. 4 is a front elevational view of the same.

FIG. 5 is a cross sectional view of the same taken on the line 5—5 of FIG. 1.

FIG. 6 is a fragmentary cross sectional view taken on the line 6—6 of FIG. 5.

The side not shown is the same as the side shown.

I claim:

The ornamental design for a jug, as shown and described.
